WINDMILL ORNAMENT

Theodore J. Netzel and Catherine M. Netzel, both of
123 3rd St., Gold Hill, Oreg.

Filed July 12, 1963, Ser. No. 75,766

Term of patent 14 years

(Cl. D34—15)

FIG. 1.

FIG. 2.

FIG. 3.

FIG. 4.

FIG. 1 is a perspective view of a windmill ornament embodying the design;

FIG. 2 is a view in elevation, looking squarely at the propeller, the parts being in the same relative positions in which they are illustrated in FIG. 1;

FIG. 3 is a view in elevation, looking directly at the back of the propeller, the parts being in the same relative positions in which they are illustrated in FIGS. 1 and 2; and

FIG. 4 is a plan view of the device, the parts being in the same relative positions as in FIGS. 1, 2 and 3.

We claim:

The ornamental design for a windmill ornament, as shown.
